UNITED STATES PATENT OFFICE

EMMETT F. KENNEDY, OF CLEVELAND, OHIO, ASSIGNOR TO THE CLEVELAND CO-
OPERATIVE STOVE COMPANY, OF CLEVELAND, OHIO, A CORPORATION OF OHIO

DESIGN FOR A STOVE

Application filed August 3, 1931. Serial No. 40,767. Term of patent 14 years.

To all whom it may concern:

Be it known that I, EMMETT F. KENNEDY, a citizen of the United States, and a resident of Cleveland, county of Cuyahoga, and State of Ohio, have invented a new, original, and ornamental Design for Stoves, of which the following is a specification, reference being had to the accompanying drawing, forming a part thereof.

In said annexed drawing:
The figure is a perspective view of a stove according to my design.

I claim:

The ornamental design for a stove as shown.

Signed by me this 28th day of July, 1931.

EMMETT F. KENNEDY.
